PROCESS OF MAKING EMBOSSED ARTICLE AND PRODUCT THEREOF

Alan E. Murray, New York, N. Y.

Application July 28, 1948, Serial No. 41,058

14 Claims. (Cl. 154—106)

1

My invention relates particularly to a process and products thereof whereby articles of sheet material of unusual properties may be produced and at a comparatively low cost with a minimum amount of labor, as for instance blotters, book covers, writing table accessories, brief cases, belts, handbags, articles of clothing, leather jackets, gloves, gauntlets, shoes, etc.

An object of my invention is to produce articles of this character having a long life and which are not subject to the usual amount of wear by abrasion or otherwise. Another object is to provide embossing which has a high relief but which is, nevertheless, sustained and maintained by materials which are of an elastic character, and which may have a backing on which the elastic embossing is supported. Further objects of my invention will appear from the detailed description of the same hereinafter, whereby accurate embossings can be obtained.

While my invention is capable of embodiment in many different forms and is capable of being carried out in many different ways, for the purpose of illustration I have shown only certain forms of the products and apparatus for producing the same in accordance with my invention in the accompanying drawings, in which—

Fig. 1 shows a plan view of an embossed sheet material, such as leather, secured to a blotter, made in accordance with my invention for making group or mass-produced articles;

Fig. 2 is a cross-section of the same, taken on line 2—2 of Fig. 1;

Fig. 3 is a vertical section of an apparatus used in connection with a hydraulic or other press for producing the same, taken on line 3—3 of Fig. 4;

Fig. 4 is a plan view of the apparatus shown as removed from the hydraulic press illustrated in Fig. 3;

Fig. 5 is a plan view of a sheet of paper having a design thereon corresponding to the embossing shown in Fig. 1; and

Fig. 6 is a plan view of a blotter carrying an embossed leather thereon having an inscription made in accordance with a modification of my process for producing individualized articles, not necessarily to be made by mass production.

In the drawings, for example referring first to Figs. 1 to 5, I have shown a sheet of leather 1, preferably such as soft kid or morocco or soft calf skin, which has been treated and processed in accordance with my invention, having an embossed margin 2 around the edge of the same as well as an embossed inscription 3 thereon, the

2

margin 2 and inscription 3 being in high relief, and the same being secured to one or more layers of blotting paper 4 as hereinafter described.

In producing the embossed sheet leather 1, I first make a design 4 for producing an accurate embossing, as for example a signature or name in handwriting, with a pencil on a sheet of paper 6. Thereupon, I trace the design 5 with carbon paper onto a rigid flat plate of smooth, preferably absorbent, material such as wood, fibre board, cardboard, etc., as for example a laminated ply-wood, 7. With a narrow brush I then go over the design on the laminated ply-wood 7 so as to apply on the lines of said design a rubber cement of any desired kind, as for instance made of rubber dissolved in a volatile solvent, such as a hydrocarbon, and allow the cement to dry until it becomes tacky. Then I prepare a readily bendable cord of any desired kind, but preferably a hard twisted or woven fish line or chalk line 8 made of textile fibres, by brushing the said line or cord with more of the said rubber cement and allowing the same to dry until tacky, thus producing a tacky, readily adherent, rubber coated cord. This rubber coated cord is then cut into small pieces of any convenient length, but preferably such as to require two or more pieces thereof for each letter of the signature or name, or of such size that each piece may readily form each of the loops or straight lines of the signature made in a flat plane, as desired. These pieces of the rubber coated cord 8, while still tacky, are made to adhere end to end, to produce the lines, over the tacky outline which has been made on the ply-wood 7. The said pieces 8 firmly adhere thereto and the pieces are then pushed around with a blunt stylus until they accurately occupy the exact outlines, as desired, of the inscription, as well as the marginal lines, preparatory to producing the desired lines of the embossing. The tackiness of the cord and the lines on the ply-wood 7 enable a great deal of accuracy to be attained in conforming the pieces of cord to the desired outlines, and such as to produce the high relief of the embossing. Then I apply to the surface of the ply-wood 7 carrying the pieces of cord 8 fixed in place thereon, one or more layers of a hard coating, but preferably about two layers, of a cellulose ester solution comprising cellulose acetate, for example, carried in any desired volatile solvent or solvents. When the solvents have evaporated there remains a hard coating which is not soluble in rubber cement or rubber compositions, and an effective positive die is thus obtained comprised of the

laminated ply-wood 7 having thereon the rubber encased cords 8. A negative die 9 is then formed of a body of compressible elastic vulcanized rubber or artificial rubber, preferably "neoprene," which may be of any desired thickness but which, for instance, is $\frac{1}{4}$ " in thickness, or, as for instance, about double the thickness of the laminated ply-wood 7. The surface of the rubber plate 9 can be rough or smooth, but preferably in using the die I first use one face which is smooth and then the opposite face which has a pebble-like surface for causing the rubber plate 9 to conform itself completely to the cords 8 and the surface 7 supporting the cords. Furthermore, the rubber plate 9 may be supported upon a wooden block 10, to the upper face of which there are attached, by screws 11, lateral guides 12 and 13 and longitudinal smaller guides 14 and 15, the said guides being made of wood or of any other desired material, so as to be held in place by the screws 11 and the negative die wooden block 10. The positive die 7 and the negative die 9 with its supporting plate 10, can then be placed between upper and lower jaws 16 and 17 of a hand screw press so that any desired amount of pressure may be exerted thereon by power or otherwise.

Thereupon, I prepare two solutions of any adhesives desired, but preferably of "neoprene" latex. In this connection, I use latex, which is a long established well known liquid comprising a pre-vulcanized latex or a self-vulcanizing latex or a pre-vulcanized or self-vulcanized synthetic rubber substitute, as for instance "neoprene," in the form of a liquid, that is to say a water suspension of the rubber or rubber substitute prepared so as to be self-vulcanizing when allowed to set. Also, I prefer to use two different strengths or consistencies of the said liquid latex, which I may denominate for the purposes herein as

- #1—thin "neoprene" latex having the consistency of thick milk
- #2—thick or thickened "neoprene" latex having the consistency of a very heavy cream.

These are both well known commercially available liquids known as "neoprene" latex, and which will, for convenience, be referred to hereinafter merely as "latex." The thin latex #1 can, if desired, be prepared by adding two parts of water by volume to one part by volume of the thickened latex #2. Thereupon I take a sheet of flat soft kid leather of any desired color, or any soft grained leather 1, generally called morocco or kangaroo, or a very soft calf skin, but which may be any soft grained leather. This sheet of flat leather 1 is then saturated by applying with a brush, on the flesh side of the leather, the thin latex #1, after which the excess of the latex is brushed off. Then I immediately brush onto the leather, on the flesh side, some of the thick #2 latex so as to make a surface covering over the entire surface of the impregnated leather.

The negative rubber die pad 9 is now immersed in soapy water at a temperature of about 150° F., or any other desired temperature, which requires generally from five to ten minutes. This makes the pad 9 soft and wet, and the soapiness thereof prevents it from sticking to the leather containing the latex. From time to time, during the time when the negative die pad 9 is being used the pad can be again immersed in this way to maintain the properties thereof just referred to. Thereupon, I apply an emollient miscible with the water of the latex, such as a soap and

preferably saddle soap, on a cloth moistened with water to the hair side of the leather 1 and rub it in with the cloth in order to soften the hair side of the leather and to effectively remove all unabsorbed latex that might be on this side of the leather. The flesh side of the leather 1, while wet with the latex, is now placed against the hard cords 8 which are encased in the hard cellulose ester, next to the positive die 7 substantially immediately, before the latex has gelled and before it has set. The jaws 16 and 17 of the hand screw press are now brought together so as to thereby apply power pressure thereto and to produce any desired pressure greater than mere hand pressure, as for example 1000 to 4000 lbs., so as to produce the impression of the embossing in the leather 1 before the latex which is absorbed in the leather has gelled and to fill the cavities of the embossing with the latex. The pressure of the hand press causes the thick latex #2 to penetrate thoroughly every part of the leather 1 and into the concavities of the embossing over the cords 8, and this makes the latex gel quickly because of the interaction of the thick latex and the constituents of the leather, as for instance the chromium compound or compounds which are normally present in chrome tanned leather when the leather has been produced by chrome tannage, although, as a matter of fact, the constituents which have been added to or formed in substantially any leather which has been tanned by the various tanning processes will cause the latex to gel almost immediately under the pressure applied. The treated leather 1 is allowed to stay in the press for any desired time, but usually three minutes is sufficient to cause the latex to gel. The jaws of the press 16 and 17 are then separated and the leather 1 can be lifted off readily with the positive die 7 as it will not stick to the soapy rubber surface of the negative die pad 9. The hair side of the treated leather 1 is then again rubbed with the emollient, such as saddle soap and a cloth wet with water to remove the unabsorbed latex from the surface of the hair side of the leather, after which the leather is stripped off from the positive die 7. The flesh side of the leather thus freed from the positive die 7 is then brushed with some of the thick latex #2, so as to fill the concavities of the embossing with the said latex and then, while this latex is still wet, I apply a backing of an absorbent material, such as the blotter 4, to the treated leather 1, to which the said blotter 4 becomes firmly adherent. When the latex has entirely gelled, which generally takes place in a few minutes, the latex of rubber or rubber substitute will be found to have filled the interstices of the leather and the concavities of the embossing entirely, and after standing for a longer period, as for instance about ten days, the rubber will be found to have completely set into a tough resistant and elastic solid. This preserves the detail of the embossing in the impregnated leather, which is set into the embossed form with a high relief and which is maintained elastically in this form due to the latex filling all the interstices of the relief portions of the embossed leather. The embossing thus obtained, accordingly, remains permanent as well as waterproof, and is not subject to any appreciable material deformation or damage due to use. This is particularly important in articles which are subjected to continued use, as for instance in the articles named above. Accordingly, the articles

thus produced are notable for their longevity and freedom from wear.

The modification of my invention as set forth in Fig. 6, is particularly suitable in connection with the making of individualized embossed articles and which do not require mass production. This is particularly suitable for individualized articles having thereon, for instance, the individual signatures of their respective owners. For example, in making a desk blotter I make a design on paper, of the embossing desired, similar to that on the sheet of paper 6 above referred to, and then I trace over this onto a flat smooth, preferably absorbent, sheet of material, such as a blotter 18, with the aid of carbon paper, the design which is to be embossed thereon. The design of the embossing thus produced on the blotter 18 is then painted over with the rubber cement, as described previously. Also, one or more cords 19 are coated with rubber cement, as in the case of the cords 8 previously described, and while the design and the cords 19 are still tacky the cords, cut into small pieces, are applied to the design and made to adhere to one another thereon end to end. With a stylus, as above described, the cords are shoved into place or bent around to form the accurate design of the embossing. The cords 19 and the adjacent face of the blotter are thereupon given one or more coatings of a hard coating, such as the cellulose ester, for instance the cellulose acetate solution above referred to, to completely cover the cord and to form a stiff or hard coated backing. A sheet of leather 20 of the character above described is then impregnated and coated throughout the body thereof, as described above in connection with the sheet of leather 1. The leather 20, while wet, is now placed, flesh side down before the latex is dry, on top of the blotter 18 carrying the rubber coated cords 19. A rubber plate, such as the rubber plate 9, is then pressed down on the top of the leather by the screw hand press to provide power pressure, by which I mean greater than mere hand pressure, first with the smooth side of the plate 9 and then with the rough side of the plate 9 against the leather, which fills the concavities of the embossing with the latex. A blunt stylus can then be moved over the top or hair side of the leather 20 around both sides of each of the cords 19 in the design to be embossed and the emollient, such as saddle soap, with the aid of a wet cloth, is rubbed over the outer or hair surface of the leather 20. This procedure, alternately with the stylus and the saddle soap, is repeated several times until the embossed design shows in very high relief, and which is even higher than the relief of the embossing shown on the sheet of leather 1. In this way, and due to the pressure of the rubbing and with the stylus, the latex thoroughly impregnates the leather 20 and quickly gels due to the pressure applied and to the effect of the constituents of the tanned leather. Some of the latex even comes through to the outer surface of the leather 20 in the course of the pressure thus applied, which is removed by the said rubbing. Accordingly, the latex completely fills the interstices of the leather as well as the concavities on the under surface of the embossed or raised portions of the design. The underneath side of the coated blotter 18 can then have fastened thereto, with an adhesive or otherwise, one or more additional blotters 21 and 22, to form a backing.

Accordingly, the finished product, especially after the latex has become completely set, in the form of my invention in Fig. 1 as well as in the

previous form shown in Fig. 6, comprises an embossed leather article completely impregnated with the rubber which has set into a form that was unnatural for the flat sheet of leather used in making the same, and also in such a manner that the set latex in the curvatures or concavities of the embossing will retain the leather permanently in the form of the embossing of an integral whole. An elastic, waterproof, permanent embossing is thus obtained which, because of its great elasticity, is not subject to the usual wear and damage by abrasion, of embossed materials as previously made. These advantageous characteristics are particularly valuable in the articles of this character owing to the continual rubbing and use to which articles of this kind are normally subjected. Also, the embossed leather, notwithstanding its completely natural appearance, has nevertheless coalesced throughout with the impregnating rubber so that the resulting article, while having the appearance of natural leather, has the advantageous properties and characteristics of the rubber which is present throughout the body of the same.

While I have described my invention above in detail I wish it to be understood that many changes may be made therein without departing from the spirit of the same.

I claim:

- 30 1. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape.
- 35 2. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape.
- 40 3. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape, the leather also having had latex introduced into the concavities of the embossing before the first mentioned latex has completely set after removing the pressure.
- 45 4. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape, the leather also having had latex introduced into the concavities of the embossing before the first mentioned latex has completely set after removing the pressure, the embossed leather having a stiff coated flat backing adherent to the leather below the embossing.
- 50 5. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape, the leather also having had latex introduced into the concavities of the embossing before the first mentioned latex has completely set after removing the pressure, the embossed leather having a stiff coated flat backing adherent to the leather below the embossing.
- 55 6. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape, the leather also having had latex introduced into the concavities of the embossing before the first mentioned latex has completely set after removing the pressure, the embossed leather having a stiff coated flat backing adherent to the leather below the embossing.
- 60 7. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape, the leather also having had latex introduced into the concavities of the embossing before the first mentioned latex has completely set after removing the pressure, the embossed leather having a stiff coated flat backing adherent to the leather below the embossing.
- 65 8. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape, the leather also having had latex introduced into the concavities of the embossing before the first mentioned latex has completely set after removing the pressure, the embossed leather having a stiff coated flat backing adherent to the leather below the embossing.
- 70 9. A process which comprises producing an embossed leather containing in the leather and in the concavities of the embossing a unitary continuous body of latex by embossing leather wet to a point approximating saturation throughout the body thereof with latex, embossing the leather while wet by applying power pressure to fill the concavities of the embossing with the latex while wet, pressed from within the body of the leather, and allowing the latex to gel while maintaining the leather in the embossed shape, the leather also having had latex introduced into the concavities of the embossing before the first mentioned latex has completely set after removing the pressure, the embossed leather having a stiff coated flat backing adherent to the leather below the embossing.

tinuous body of latex by embossing leather wet throughout the body thereof with latex, then applying an amount of a thicker latex, embossing the leather by pressing the leather in a plane on one side bodily against a linear opposing force on the other side while wet and allowing the latex to gel while maintaining the leather in the embossed shape.

5. A process which comprises producing an embossed leather containing in the leather and in the concavities of the embossing a unitary continuous body of latex by embossing leather wet to a point approximating saturation throughout the body thereof with latex, then applying an amount of a thicker latex, embossing the 15 leather by pressing the leather in a plane on one side bodily against a linear opposing force on the other side while wet and allowing the latex to gel while maintaining the leather in the embossed shape, the leather also having had latex introduced into the concavities of the embossing before the first mentioned latex has completely set after removing the pressure.

6. A process which comprises producing an embossed leather containing in the leather and in the concavities of the embossing a unitary continuous body of latex by embossing leather wet to a point approximating saturation throughout the body thereof with latex, then applying an amount of a thicker latex, embossing the 25 leather by pressing the leather in a plane on one side bodily against a linear opposing force on the other side while wet by applying power pressure to fill the concavities of the embossing with the latex pressed from within the body of the leather and allowing the latex to gel while maintaining the leather in the embossed shape, the leather also having had latex introduced into the concavities of the embossing before the first mentioned latex has completely set after removing the pressure, the embossed leather having a stiff coated flat backing adherent to the leather below the embossing.

7. An embossed leather comprising a plane leather surface with concavities carrying therein a continuous body of gelled latex filling the concavities of the embossing therein and extending throughout the formed body of the leather.

8. An embossed leather comprising a plane leather surface with concavities carrying therein a continuous body of gelled latex filling the embossing therein and extending throughout the formed body of the leather, the embossing having the form of cords pieced end to end.

9. An embossed leather comprising a plane 55 leather surface with concavities carrying therein a continuous body of gelled latex filling the embossing therein and extending throughout the formed body of the leather, the embossing having the form of cords pieced end to end, said embossed leather having a stiff coated backing adherent thereto below the embossing.

10. An embossed leather comprising a plane leather surface with concavities carrying therein

a continuous body of gelled latex filling the embossing therein and extending throughout the formed body of the leather, the embossing having the form of cords pieced end to end, said cord also having a hard coating thereon.

11. An embossed leather comprising a plane leather surface with concavities carrying therein a continuous body of gelled latex filling the embossing therein and extending throughout the formed body of the leather, the embossing having the form of cords pieced end to end, said embossed leather having a stiff coated backing adherent thereto below the embossing, said cord also having a hard coating thereon.

12. An embossed leather comprising a plane leather surface with concavities carrying therein a continuous body of gelled latex filling the concavities of the embossing therein and extending throughout the formed body of the leather, the embossing having therein also a cord.

13. The process which comprises producing an embossed leather containing in the leather and in the concavities of the embossing a unitary continuous body of latex by embossing leather wet throughout the body thereof with latex, embossing the leather while wet by applying pressure to fill the concavities of the embossing with the latex while wet, pressed from within the body of the leather, and allowing the latex to gel by accelerating the setting thereof due to a constituent present in the leather, while maintaining the leather in the embossed shape.

14. A process which comprises producing an embossed leather containing in the leather and in the concavities of the embossing a unitary continuous body of latex by embossing leather wet throughout the body thereof with latex, embossing the leather while wet by applying pressure to fill the concavities of the embossing with the latex while wet, pressed from within the body of the leather, and allowing the latex to gel, by accelerating the setting thereof due to a constituent present in the leather, while maintaining the leather in the embossed shape, the leather also having had latex introduced into the concavities of the embossing before the first mentioned latex has completely set after removing the pressure.
